(57) **CLAIM**

The ornamental design for the electronic device support, as
shown and described herein.

DESCRIPTION

FIG. 1 is a perspective view of the electronic device support;
FIG. 2 is a front view of the electronic device support of FIG.
1;

FIG. 3 is a back view of the electronic device support of FIG.
1

FIG. 4 is a side view, taken from the right side of FIG. 2, an
opposing side view being the mirror image thereof;

FIG. 5 is a top view of the electronic device support of FIG. 2;
and,

FIG. 6 is bottom view of the electronic device support of FIG.
2.
